TRAFFIC-LINE TOY

Georg Einfalt, Nuremberg, Germany

Application January 25, 1937, Serial No. 122,617

4 Claims. (Cl. 246—117)

This invention relates to a toy representing a traffic line, the main object of the invention being to demonstrate to a child the modern arrangements of traffic control at crossing points of the roads, by means of differently coloured light signals, in such a manner that the child can control the traffic at will, viz., the stopping and starting of the vehicles on the traffic line by the simultaneous change-over of the differently coloured lights. This object is attained by means of a rail track of any desired shape, at the crossing point of which there is provided a traffic controlling light comprising electric lamps fed by a dry battery and mounted in a suitable enclosure provided with differently coloured windows, a suitable change-over switch being used for switching over the lights from one direction of control to the other, the said change-over switch being mechanically operated by connecting means provided between it and means arranged along the track, and adapted to bring a travelling car to a standstill or allow it to pass.

The mechanism preferably comprises a disc arranged centrally at the crossing point and pivotally connected by means of bars with platforms arranged in the middle of the track, opposite corresponding openings formed therein, and adapted to be sunk with respect to the surface of the road or be raised so as to be flush therewith, when the said disc is mechanically turned from a point of control, the said disc being also adapted to operate the change-over switch. The various connections are such that when the disc is in one position, the two platforms arranged along the one track are sunk, so that the cars thereon are brought to a standstill and the light controlled by the switch shows red (stop) along this track, whilst the platforms along the other track crossing with the first one are flush with the surface of the track and the cars can proceed along it, the light controlled by the switch showing green (go) along this track. With the interconnecting disc in the other position, the positions of all the platforms and colours of light are reversed along the two crossing tracks.

Other features of the invention are hereinafter described and claimed in the appended claims.

Referring to the accompanying drawings illustrating the invention by way of example,

Figure 1 is a perspective view of a traffic line in the form of an 8;

Figure 2 is an enlarged plan view of the crossing portion of the line;

Figure 3 is a cross-section of the track;

Figure 4 shows a longitudinal section along

the portion of the track containing a displaceable platform with a car standing over it;

Figures 5 and 6 show in plan view and elevation respectively the part of the traffic-line from which the traffic is controlled and

Figure 7 is a perspective view of the mast supporting the control lights within a lantern shown in section.

The actual 8-shaped traffic-line is constituted by a cross-member 1 and the two arcuated tracks 10 2, the whole being built up of sections joined together at a. As will be seen from Figure 3, the track has a special profile, being made hollow underneath for the accommodation of the operating mechanism. 3 is a mast carrying the 15 lantern 4 of the control lights and adapted to be removably attached to the cross-member 1, in such a manner that the four sides of the lantern, each provided with a green and red window, face the four directions of the track respectively. 5 20 is a rotary disc, pivoted underneath the cross-member 1, being mechanically connected to the displaceable platforms and adapted to effect the change-over from one light control to the other. For this purpose, the one end 6 of the movable 25 contact of the switch, which receives current from one end of the battery 7 through the lead 8, conducts it to the other end 9 of the movable contact, which, according to the position of the disc 5, to which the movable contact member is attached through an insulating member 10, makes contact with either the fixed contact 11 or the fixed contact 12, mounted in an insulated manner on the cross-member 1. When the lantern mast 3 is in position, two spring contacts 11' and 12' provided at its lower end make contact with the said fixed contacts 11 and 12 respectively, and by means of wires 11'' and 12'' the current is led to the one terminal of the glow lamps 13 and 14 respectively; the current, after passing through 40 the lamp to its other terminal, returns to the other end of the battery which, like the one end of the lamps 13 and 14, is connected to the metal frame of the toy. The lantern 4 is divided by a partition 15 into two compartments lying one 45 above the other and respectively accommodating the glow lamps 13 and 14.

The four sides of the lower compartment of the lantern 4 are provided with coloured windows 16, and similarly, the upper compartment with 50 coloured window 17. In each compartment two opposite windows are green and the other two opposite ones red, but the colours are displaced in the lower compartment as compared with the upper one, viz., whenever there is a red 55

window in one lantern side of the upper compartment, there is a green one in the same side of the lower compartment, and vice versa.

The means for actuating the rotary disc 5 and the mechanical connection between the latter and the displaceable platforms 23, 24, four of which are provided, viz., one on each part of the track near the crossing point, will now be described.

10 The actuating means comprises a member 18 which is pivoted to a lug 18' attached to the track and is linked with the disc 5 by means of a bar 19, one end 19' of which, bent at right angles, passes through an elongated slot 18'' in the lug 18' and engages loosely in a hole in the pivoted member 18. The disc 5 is also linked with the platforms 23, 24 by means of bars 21 and 22 respectively, the platforms being so mounted underneath the track opposite elongated rectangular recesses in the track, that, when the disc is turned in one direction under the control of the actuating member 18, two of the platforms, in alignment along the track, say the platforms 23, will come to lie near the surface of the track 15 and the other two, say 24, will be caused to drop, so as to lie below its surface, and vice versa, when the member 18 is actuated so as to turn the disc 5 in the opposite direction, the platforms 24 being then raised near the surface of the track 20 and the platforms 23 caused to drop. When the rotary disc is in the first position, the switch connected therewith causes the green windows, facing the track containing the raised platforms 23, and the red ones, facing the track 25 containing the dropped platforms 24, to light up, and vice versa when the disc 5 is in the second position, the red windows, facing the track containing the dropped platforms 23, and the green windows, facing the track containing the 30 raised platforms 24, will light up along these tracks respectively.

The raising and dropping of the platforms is ensured by the following construction (see Figure 4). The longitudinal walls 25 formed on the 45 sides of the rectangular recess in the track facing the platform are bent in at the ends 26, thereby forming sliding bearing surfaces for the platform which has side walls 27 partly cut away at 28 in such a manner that the walls 27 merge gradually into 28 by the inclined portions 28'. 50 When the disc 5 is in one position two of the platforms in one alignment rest with their side walls 27 on the bent-in ends 26 of the longitudinal walls 25 so that these platforms are in 55 their raised position, whilst the other two in the other alignment, crossing the first one, rest with their cut-away portions 28 on the said ends 26 of the longitudinal walls, so that these platforms are in their dropped position.

60 Use may be made of any suitable vehicle toy in combination with the track hereinbefore described, preferably of a spring-driven motor car provided with a suitable clockwork mechanism. It is, however, necessary to provide the vehicle 65 with means which will stop the working of the clockwork mechanism when the vehicle comes over a platform facing a red light and is thus in a dropped position.

Figure 4 shows over the platform 24 a vehicle 70 29 provided with a clockwork mechanism 30 of any well known construction. On an intermediate spindle 31 of this mechanism there is mounted a two-arm control lever, one arm 32 of which, a long one, comes to lie over the longitudinal axis of the platform 24, whilst a shorter 75

arm 33 is provided with a projection 34 which engages with the toothed wheel mounted on another intermediate shaft of the clockwork mechanism. When the car is running along the track, the arm 32 slides along its surface and also along 5 the platforms which happen to be raised to the surface of the track; however, as soon as the car reaches a dropped platform, the arm 32 drops too, owing to its weight, thereby causing the projection 34 of the arm 33 to come into engagement with the toothed wheel 35 and the clockwork mechanism to stop, whereby the car is brought to a standstill. This corresponds, of course, to a red indication of the light, since such an indication corresponds to that position of the 15 platform in which the same lies below the surface of the track. As soon as the disc 5 is turned under the control of the member 8, so that the light is changed to green and, simultaneously therewith, the platform is raised to the surface 20 of the track, the arm 32 is also raised, and the toothed wheel 35 is disengaged by the projection 34 of the arm 33, so that the clockwork mechanism is again put into operation, with the result that the car starts running again along the 25 track.

It is to be understood that the details for carrying the invention into effect may be modified in various respects, such as by using a different 30 track than one in the form of an 8, a different mechanism on the car operated by the raising and dropping of the platform, more than two coloured lights, viz., also yellow etc., without in any way departing from the spirit of the invention.

What I claim is:—

1. A toy traffic-line comprising two tracks crossing each other at a crossing point and having on each side of the crossing point a recess elongated in the longitudinal direction of the 40 track, in combination with signalling means indicating that the traffic along one track is free to move and along the other one that it has to stop, an automatically driven vehicle on the tracks, sliding elongated platforms capable of 45 bringing the said vehicle to a stop, said sliding elongated platforms corresponding to and filling the elongated recesses in the track and being capable of dropping below the surface of the track, whereby the recesses are exposed, means for simultaneously operating the elongated platforms, so that on one track the said platforms will not interfere with the running of the vehicle and on the other track they will bring it to a stop, and for simultaneously operating the signalling 50 means which indicate that along the one track the vehicle is free to move and along the other track that it has to stop; means on the track which are normally operative to maintain the said platforms inoperative, except when the vehicle passes over an exposed recess, and a stop mechanism on the vehicle with which the sliding platforms are adapted to co-operate to prevent or permit its operation.

2. A toy traffic-line as claimed in claim 1, in which the means for operating the said platforms comprise a rotary disc arranged underneath the crossing point of the tracks, an actuating member, a bar linked to the actuating member and to the said rotary disc, and bars linked to the 60 rotary disc and each one of the said platforms.

3. A toy traffic-line as claimed in claim 1, in which the means for operating the said platforms comprise a rotary disc arranged underneath the crossing point of the tracks, an actu-

ating member, a bar linked to the actuating member and to the said rotary disc, and bars linked to the rotary disc and each one of the said platforms, and in which the signalling means comprise a lantern of square cross-section having two separate compartments, one above the other, an electric glow lamp in each compartment, windows of one colour on two opposite sides of each compartment and windows of another colour on the other two opposite sides thereof, the colour of each of the windows in the lower compartment being different from that of the window above it in the upper compartment of the lantern, an electric battery connected to the lamps in the said two compartments of the lantern and a change-over switch adapted to be operated by the said rotary disc.

4. A toy traffic-line as claimed in claim 1 and in which the operating mechanism for the vehicle consists of a clockwork mechanism and a two-armed lever interposed in the said clockwork mechanism in such a manner that one arm thereof hangs down and rests by its weight on the track in alignment with said recesses, and its other arm lies in the proximity of a toothed wheel of the clockwork mechanism, whereby upon the vehicle coming over a dropped platform along the track, the arm of the two-armed lever resting on the track will drop on the said platform owing to its weight, and the other arm will come into engagement with the toothed wheel in its proximity, thereby stopping the clockwork mechanism and the running of the vehicle.
